LOOSE LEAF BINDER

Adolph G. Lotter, Milwaukee, Wis., assignor to
Stationers Loose Leaf Company, Milwaukee,
Wis., a corporation of Wisconsin

Application May 19, 1938, Serial No. 208,785

9 Claims. (Cl. 129—24)

This invention relates to binders, principally the large loose leaf record book type, and like the copending applications of Adolph G. Lotter, Serial Nos. 178,956 and 178,957, both filed December 9th, 5 1937, relates particularly to mechanism for automatically connecting the binder posts with the hingedly connected back and covers during closure of the binder.

Binders of this type generally comprise a back 10 to which the covers are hingedly connected, and binder posts which pass through the body of leaves and are detachably connected either with the covers or the back. The actual connection is usually effected by means of pintle bars carried 15 either by the covers or back and slidably engageable in loops or openings in the ends of the binder posts.

Disengagement of the pintle bars from the binder posts is effected by a manually applied 20 pull on the pintle bars, but re-engagement, as noted hereinbefore, is desirably effected automatically upon closure of the binder. The two copending applications mentioned are directed to this same broad object, but it has been found 25 that smoother operation is possible with the simplified construction of the present invention.

The specific object of this invention, therefore, 30 is to improve the mechanism employed for automatically effecting re-engagement of the pintle bars with the binder posts during closure of the binder with a view toward obtaining smoother operation and a more simplified mechanical construction.

With the above and other objects in view which 35 will appear as the description proceeds, this invention resides in the novel construction, combination and arrangement of parts substantially as hereinafter described, and more particularly defined by the appended claims, it being understood 40 that such changes in the precise embodiment of the hereindisclosed invention may be made as come within the scope of the claims.

The accompanying drawings illustrate two 45 complete examples of the physical embodiment of the invention constructed in accordance with the best modes so far devised for the practical application of the principles thereof, and in which:

Figure 1 is a top view of a portion of a loose 50 leaf binder of the type to which this invention appertains, with a part broken away and in section;

Figure 2 is a cross sectional view through the 55 binder, illustrating the manner in which the

posts are detached from the hingedly connected covers and back;

Figure 3 is an enlarged top view of a portion of a binder, with parts broken away and in section to illustrate specifically the manner in which re-engagement of the pintle bar with the binder posts is automatically effected;

Figure 4 is a detail sectional view taken through Figure 3, on the plane of the line 4—4; and

Figure 5 is a view similar to Figure 3, but illustrating a slightly modified embodiment of the invention.

Referring now particularly to the accompanying drawings in which like numerals indicate like parts, the numeral 5 designates the back of 15 a binder of the character described to which covers 6 are hingedly connected, as at 7. The body of leaves 8 is held in place by a plurality of binder posts 9, generally four, detachably connected at their opposite ends to the covers by 20 means of pintle bars 10.

The pintle bars 10 are slidably mounted in flat 25 tubular guideways 11 on the inner edges of metal plates 12 which form part of the covers. Aper- 30 tures in the edges of these guideways enable the insertion into the guideways of the binder post ends when the binder is closed. With the post ends so positioned, pins 13 on the pintle bars are projectable through holes 14 in the outer ends of the posts to connect the posts with the hinged- 35 ly connected back and covers.

Detachment of the posts to permit insertion or removal of sheets requires merely disengaging the pins 13 from the binder posts which can be effected by manually applying a pull on the pintle bars. To facilitate such manual application of force, one end of each pintle bar is provided with a finger grip, indicated generally 40 by the numeral 15 in Figure 1.

During closure of the binder, it is desired to 45 have the pintle bars automatically re-engaged with the binder posts, and to this end mechanism is provided for returning the pintle bars into post engaging position, this mechanism being pro- 50 pelled by the closure of the covers. Inasmuch as 55 the construction of the pintle bar actuating mechanism is the same at both sides of the binder, a description of one of them will suffice for both.

This mechanism comprises an actuator 16 50 somewhat in the shape of a bell crank lever piv- 55 oted as at 17 to the metal plate 12 with one end 18 thereof in position to engage an abutment 19 formed by a notch in the pintle bar. A rivet 21 fixed to the plate 12 and disposed in an arcuate 55

slot 22 in the actuator serves to limit the motion of the actuator and also cooperates with the pivot 17 in mounting the actuator on the plate.

The opposite end 23 of the actuator, which in effect constitutes the short arm of the bell crank lever, is pivotally connected as at 24 with a link 25. The link 25 is guided for motion substantially transverse to the sliding axis of the pintle by means of a rivet 26 fixed to the plate 12 and operating in a slot 27 in the link.

Hence, it will be seen that upon an outward push on the link 25, the actuator is swung about its pivot 17 to slide the pintle bar into post engaging position. Such motion is imparted to the link 25 during closure of the cover by means of a cam 28 fixed to the back and lying in the path of the adjacent end 29 of the link, as clearly shown in Figure 4, to force the link outwardly as the cover is swung from a fully open position toward its closed position.

If desired, the actuator may be in the form of a gear segment 30, as shown in Figure 5, with its teeth meshing with a rack 31 on the pintle bar. In other respects, with the possible exception of the specific shape of the link 25, this modified embodiment of the invention is like that described.

The modified construction, however, has the added advantage of maintaining a positive driving connection between the pintle bar and the actuator at all times so that in the event the pintle bar is pulled out while the cover is closed, which would then prevent opening of the cover by disposing the end of the link over the cam, the parts can be restored to their positions they occupy when the pintle bar is in post engaging position, to permit unrestricted opening of the cover.

From the foregoing description taken in connection with the accompanying drawings, it will be readily apparent to those skilled in the art that this invention materially simplifies the mechanism for automatically effecting re-engagement between the pintle bars and binder posts in record loose leaf binders, and that smooth operation is assured.

What I claim as my invention is:

1. In a loose leaf binder of the character described; a back; a cover hinged to the back; a binder post; a pintle bar slidably carried by one of said members and engageable with engagement with the binder post; a lever pivotally mounted on the cover and operable to slide the pintle bar into post engaging position; and cooperating parts carried by the cover and the back for actuating the pivoted lever during closure of the cover.

2. In a binder of the character described: a back member; a cover member hinged to the back member; a binder post; a pintle bar slidably carried by one of said members and engageable with the binder post to connect the binder post with said hingedly connected members; a lever engaging the pintle bar and pivotally mounted on the member which carries the pintle bar; and cooperating means carried by said members and operable during closure of the cover to actuate the lever for sliding the pintle bar into post engaging position.

3. In a binder of the character described: a back member; a cover member hinged to the back member; a binder post; a pintle bar slidably carried by one of said members and engageable with the binder post for connecting the binder post with said hingedly connected members; an actuator mounted on the member which carries the pintle bar and operable on the pintle bar to

slide the same into post engaging position; cooperating parts carried by said hingedly connected members engageable during closure of the cover to effect relative motion between the cooperating parts; and means connecting one of said parts with said actuator so that the relative motion between the cooperating parts produced by closure of the cover moves the actuator to slide the pintle bar into post engaging position.

4. In a binder of the character described: a back member; a cover member hinged to the back member; a binder post; a pintle bar slidably carried by one of said hingedly connected members and movable to and from engagement with the binder post to connect the binder post with the hingedly connected members; an actuator pivotally mounted on the member which carries the pintle bar and operable on the pintle bar to slide it into post engaging position; a cam carried by the other of said members; and a cam follower connected with the actuator and engageable with said cam during closure of the cover to move the actuator in a direction to slide the pintle bar into post engaging position.

5. In a binder of the character described: a back member; a cover member hinged to the back member; a binder post; a pintle bar slidably carried by one of said hingedly connected members and movable to and from engagement with the binder post to connect the binder post with the hingedly connected members; an actuator pivoted to the member which carries the pintle bar and operable on the pintle bar during swinging motion thereof in one direction to slide the pintle bar into post engaging position; a link connected with said actuator and guided for movement substantially transverse to the axis of the pintle bar and having a part disposed adjacent to the hinged connection between the cover member and back member; and cam means carried by the back member and operable upon said part of the link during closure of the cover member for moving said link and the actuator to slide the pintle bar into post engaging position.

6. In a binder of the character described: a back member; a cover member hinged to the back member; a binder post; a pintle bar slidably carried by one of said hingedly connected members and movable to and from engagement with the binder post to connect the binder post with the hingedly connected members; a rack on the pintle bar; a gear segment pivoted to the member which carries the pintle bar and meshing with the rack; and means operable during closure of the cover to actuate the gear segment in a direction to slide the pintle bar into post engaging position.

7. In a binder of the character described: a back member; a cover member hinged to the back member; a binder post; a pintle bar slidably carried by one of said hingedly connected members and movable to and from engagement with the binder post to connect the binder post with the hingedly connected members; a gear segment pivotally mounted on the member which carries the pintle bar; a rack carried by the pintle bar and meshing with the teeth of the gear segment so that the gear segment and the pintle bar are joined for concurrent motion; and cooperating parts carried by said hingedly connected members for positively actuating the gear segment in a direction to slide the pintle bar into post engaging position during closure of the cover member.

8. In a binder of the character described: a back member; a cover member hinged to the back

member; a binder post; a pintle bar slidably carried by one of said hingedly connected members and movable to and from engagement with the binder post to connect the binder post with the hingedly connected members; an abutment on the pintle bar; an actuator pivoted to the member which carries the pintle bar and having a part engageable with said abutment so that movement of the actuator in one direction slides the pintle bar into post engaging position; and cooperating means carried by said hingedly connected members for so moving the actuator during closure of the cover member.

9. In a loose leaf binder of the character described: a back; a cover hinged to the back; a binder post; a pintle bar slidable to and from engagement with the binder post; a pivoted lever operable on the pintle bar to slide it into post engaging position; and cooperating parts carried by the cover and the back engageable during closure of the cover and operable to propel said lever to slide the pintle bar to its post engaging position.
